UNITED STATES PATENT OFFICE.

ANTOINE GIRIN, OF LYON, FRANCE.

CARBURETOR.

Application filed June 10, 1920. Serial No. 388,005.

To all whom it may concern:

Be it known that I, ANTOINE GIRIN, a citizen of the French Republic, of Lyon, France, have invented certain new and useful Carburetors, of which the following is a specification.

This invention relates to improvements in carburetors for internal combustion engines.

The object of the invention is to provide a carburetor in which the actuation of a lever causes, through suitable mechanism, the regulation of the size of the air and fuel delivery passages in accordance with the particular conditions existing as to atmospheric pressure, temperature, etc.

Figure 1 is a vertical section of the carburetor with parts in elevation.

Fig. 2 is a horizontal section on line 2-2 of Fig. 1.

Fig. 3 is an enlarged perspective view of the valve operating mechanism.

Fig. 4 is an enlarged detail section of the upper end of the nozzle.

The body 1 of the carburetor supports all the various parts thereof. Within the cylindrical part of said body, which serves for the passage of the mixture and as a connection with the motor, is a Venturi tube 2 acting as a diffuser and increasing the suction at the end of the fuel nozzle, said tube being open at its base. In a recess formed in the wall of the intake passage surrounding the Venturi tube is received a vertically slidable sleeve 4. This sleeve normally occupies its lowermost position, seated on a valve seat 4^a, formed on the upper surface of a fuel chamber 5 provided in the base of the body 1. It will be seen that the sleeve 4 constitutes an air valve which, in its lowermost position, cuts off the flow of air into the intake passage of the carburetor.

Inside a fuel nozzle 8 which is housed at the center of the diffuser tube 2 and is fixed upon the fuel chamber 5 of the body 1, there is positioned a vertically slidable tubular piston 9 surmounted by a head 10. At the top of the nozzle is a circular series of ports 11, which can be partially or entirely choked by thin, vertical rods or needles 12 supported by the head 10 of the slidable piston 9.

To operate the sleeve 4 and the piston 9 simultaneously, a quadrant-shaped member 37 is provided, said member being mounted on a horizontal rock shaft 38 operated by means of the lever 39.

Notches 40 and 41, provided one on each side of the quadrant 37, engage with pins carried by two movable rods 18 and 39^a which are mounted to slide vertically in guide openings formed in body 1. The rod 39^a has fixed to its lower end a fork or collar 42 which seats in a groove in sleeve 4, so that the vertical movements of said rod are thus transmitted to the sleeve. The lower part 60 of the rod 18 is formed with a bore 43 and slides in a guide tube 43^a which is in communication with the fuel chamber 5.

The quadrant 37 is provided with a cam slot 44 of the desired form as determined by experiment; in which cam-slot a pin or spindle 45 is engaged. The rectilinear and vertical displacements of said spindle are effected by the rocking movements of quadrant 37, due to its engagement in said slot, 65 against the upper edge of which latter it is pressed by a spring 47. This spring is arranged in a cylindrical opening formed in the body 1, and it exerts its pressure upward against a piston 46 which is slidably 70 fitted in the cylinder and which is pivotally connected to said spindle; the arrangement being such, therefore, as to prevent the possibility of any play.

The spindle 45 has also connected to it the 75 adjacent end of a lever 48, along which slides a fulcrum block 49'. This block 49' carries a lateral pin 49 which is loosely engaged by an arm or lever 51' fixed at its lower end to a horizontal rock shaft 52; 80 said shaft being journaled in the body 1 and having fixed to it, outside of said body, a second lever 51. Operation of lever 51 will, therefore, produce an adjustment of block 49' in either direction and, in consequence, 85 a variation in the throw of lever 48; the extent of such shifting being indicated by means of the pointer 53 and graduated scale 54.

The other end of the lever 48 is engaged 100 with a pin 56 attached to the upper end of a rod 55 which slides vertically in a guide 57 in the body 1. The lower extremity of this rod extends into the fuel chamber 5 where it is connected to the piston 9 of the fuel nozzle 8 by means of a bar 58 which oscillates about a pivot 59, one end of said bar being engaged with the rod 55 and the other end with said piston. The movements 105 of the piston 9 and sleeve 4 are thus obtained 110 in strict relation to one another.

The fuel is supplied through an inlet tube

65' and flows through the mouth 65 thereof past the pointed end of a needle valve 64 and into a pair of twin float chambers 60 containing twin floats 61. These floats 5 are connected to move in unison by means of a bar 62, which latter, in turn, is connected by a fork 63 with the stem of valve 64, so that said valve will be raised when the level of the fuel falls below the centers 10 of said chambers 60. Some of the fuel also passes through the channel 68 and calibrated orifice 70 and fills the lower chamber 5.

The operation is substantially as follows: 15 The fuel passes into the nozzle and rises up to the same level as the level in the float chambers 60, i. e., slightly below the top of the nozzle. The body 1 of the carburetor is fixed at its upper part to the inlet pipe 20 of the motor. The admission of air to mix with the fuel and form the explosive mixture, is regulated by the movement of the sleeve 4.

The carburetor is constructed to give definite mixture proportions for any definite positions of the sleeve 4; but if owing to some specific operating condition it is desired to change these mixture proportions, such result may be obtained by shifting the 30 fulcrum block 49' so as to secure the mixture proportions desired.

By actuating the lever 39, the quadrant 37 simultaneously moves the sleeve 4 by means of the rod 39^a, and the piston 9 by means 35 of the cam 44, lever 48, rod 55, and bar 58. As the piston 9 progressively opens or closes the ports 11 of the nozzle 8 according to its direction of movement, it will be seen that, by giving the cam a suitable shape, experimentally determined, it is possible, for any 40 position of the sleeve 4, to obtain a corresponding size of the nozzle orifice.

Since the temperature, atmospheric pressure, density and nature of the fuel are not 45 reproduced in a constant manner in practice, it is necessary to provide easily-operable adjusting means which will permit the necessary corrections being made.

This result is obtained in the present 50 carburetor by the displacement of the fulcrum block 49' of the lever 48. It will, in fact, be understood that according as said block is displaced in one direction or the other, the vertical motions imparted to the 55 spindle 45 by the cam 44 will be increased or decreased. It follows that each movement of the piston 9 in the nozzle is modified proportionately to that of the spindle 45, so that for each movement of the sleeve 4 60 a new size of nozzle orifice answering the new conditions of the movement is obtained.

It will, therefore, be seen that it is possible 65 by the mere displacement of the lever 51 by means of a rod 97 extending to a position adjacent the dash of the vehicle

or elsewhere near the operator to bring about either the increase or the decrease or the stoppage of the fuel; the proportional correction of the cam 44 is therefore automatically obtained. A scale 54 and cooperating pointer 53 operable with the lever 51 indicates the setting of said lever for all 70 conditions of operation. There is still left for solution a case which occurs fairly frequently, viz: sudden lifting of the sleeve 4. 75 Owing to this sudden movement, the motor cannot take up the corresponding speed, as the suction at that moment is not sufficient to secure a suitable supply of fuel. This 80 drawback is obviated by means of the hollow piston 43 which, when the sleeve rises suddenly, descends with equal suddenness in the small cylinder 43^a. The air which is in the piston becomes compressed and the incompressible fuel seeks to escape through 85 the two possible outlets, viz: the nozzle and the calibrated orifice 70. If the orifice 70 and the dimensions of the piston 43 are suitable, the fuel spurts out through the nozzle in sufficient quantities to ensure a proper 90 pick-up of the motor, and this will last exactly the time required. It is to be noted that when the operation of the lever 39^a is slow, the action of the piston 43 is negligible. 95

I claim as my invention:—

1. A carburetor for internal combustion engines, comprising a casing; a fuel chamber at the base of said casing; a constant-level tank adapted to supply fuel to said chamber; a cylindrical member; a fuel nozzle in communication with said chamber mounted concentrically within said cylindrical member; a tube provided with an air inlet at its lower end surrounding said nozzle; a vertically movable sleeve surrounding said tube and guided between it and the inner wall of said cylindrical member; a needle movable within said nozzle and adapted to progressively open or close the orifice thereof; and means for effecting simultaneous progressive movements of said sleeve and said needle. 105

2. A carburetor for internal combustion engines, comprising a casing; a fuel chamber at the base of said casing; a constant-level tank adapted to supply fuel to said chamber; a cylindrical member; a fuel nozzle in communication with said chamber mounted concentrically within said cylindrical member; a tube provided with an air inlet at its lower end surrounding said nozzle; a vertically movable sleeve surrounding said tube and guided between it and the inner wall of said cylindrical member; a needle movable within said nozzle and adapted to progressively open or close the orifice thereof; means for effecting simultaneous progressive movements of said sleeve and said needle; and means for al- 115 120 125 130

tering the relative amounts of movement of said needle and said sleeve:

3. A carburetor for internal combustion engines, comprising a casing; a fuel chamber at the base of said casing; a constant-level tank adapted to supply fuel to said chamber; a cylindrical member; a fuel nozzle in communication with said chamber mounted concentrically within said cylindrical member; a tube provided with an air inlet at its lower end surrounding said nozzle; a vertically movable sleeve surrounding said tube and guided between it and the inner wall of said cylindrical member; a needle movable within said nozzle and adapted to progressively open or close

the orifice thereof; an operating member for said needle; a pivoted sector having a cam slot; a lever for actuating said sector; a vertical rod connecting one wing of said sector to said sleeve; a lever having one end pivoted in said cam slot; means for adjusting the fulcrum of the second-named lever in the horizontal direction; a second vertical rod pivoted to the other end of said second-named lever; and a centrally pivoted lever within said fuel chamber connecting the lower end of said second vertical rod to said needle-operating member.

In witness whereof I have signed this 3¹ specification.

ANTOINE GIRIN.
